UNITED STATES PATENT OFFICE.

WALTER L. MARR, OF FLINT, MICHIGAN.

MEANS FOR INCREASING THE STABILITY OF AEROPLANES.

1,104,056.

Specification of Letters Patent. Patented July 21, 1914.

Application filed July 2, 1910. Serial No. 570,136.

To all whom it may concern:

Be it known that I, WALTER L. MARR, a citizen of the United States of America, residing at Flint, in the county of Genesee and State of Michigan, have invented certain new and useful Improvements in Means for Increasing the Stability of Aeroplanes, of which the following is a specification, reference being had therein to the accompanying drawings.

In operating aeroplanes it is necessary to provide means for arresting or preventing a lateral movement if the main planes up-tilt laterally.

This invention relates to aeroplanes wherein there are means which prevent lateral movement when the machine is tilted on its main axis and are so disposed as to automatically right the machine when so thrown out of balance or out of a substantially horizontal position.

The invention consists in the matters hereinafter set forth, and more particularly pointed out in the appended claims.

In the drawings, Figure 1 is a view of an aeroplane of a bi-plane type provided with means embodying features of the invention; and Fig. 2 is a view of a modification of the device in connection with a mono-plane.

Referring to the drawings a main frame work 1, of suitable design and material, has main planes 2 disposed transversely to the frame and line of flight at a suitable angle of inclination. Forward lifting planes 3 with any preferred form of controlling device 4 and a rear balance plane 5 with rudder 6 are secured to the frame. A motor 7 with propeller 8 is used to drive the machine. The motor and frame work are so disposed that the center of gravity is below the upper main plane and is preferably at or below the lower main plane.

Stability planes 9 are secured at intervals along the under surface of the upper main plane at substantially right angles thereto and in any convenient manner, as for example, by attaching them to uprights or struts 10 of the frame. These planes are parallel to the line of flight of the machine and their lower margins are at an interval above the lower frame and of the center of

gravity of the machine or their largest effective areas and consequently their centers of resistance are above the center of gravity of the machine. As a result of this construction any sidewise movement of the machine when the main planes are tilted laterally, is prevented. Furthermore the movement of the upper plane is checked while that of the lower plane is unimpeded so that the latter tends to swing under the upper plane as the basket of a loaded parachute swings under the parachute plane. Thus the machine tends to automatically right itself and maintain a normal position.

In machines of the mono-plane type as indicated in Fig. 2, the motor and operator's station are so disposed in relation to the main plane 11 as to bring the center of gravity of the machine below the main plane. Stability planes 12 are secured at intervals below the main plane parallel to the line of flight of the machine. Their effect is the same as in the bi-plane as they check any tendency of the main plane to move laterally when tilted and the un retarded heavier portions of the machine swing under the main plane and restore the machine to proper balance and position. The stability planes can be extended or placed above the main planes if so desired.

Obviously, changes in the details of construction may be made without departing from the spirit of the invention and I do not care to limit myself to any particular form or arrangement of parts.

I claim as my invention:—

In an aeroplane, a pair of main planes disposed one above the other in spaced relation and connected at the front and rear edges thereof by vertically disposed uprights spaced apart throughout the length of said plane, a set of depending stability planes at the ends of said main planes perpendicular to the upper main plane from which they depend and having the forward and rear ends thereof connected to said uprights and maintained in parallelism to the line of flight, the stability planes of each set being spaced apart approximately the distance of their length and having the lower edges thereof above the lower main

plane and providing air passages below and transversely of the upper main plane, and a motor disposed on the frame in such relation to said stability planes that the greater effective area of the stability planes is above the center of gravity of the aero-plane.

In testimony whereof I affix my signature in presence of two witnesses.

WALTER L. MARR.
